FIG. 2.

FIG. 1.

FIG. 3.

To all whom it may concern:

Be it known that we, Otto F. Stock, a citizen of the United States, residing at Columbus, in the county of Franklin and State of Ohio, and Horace C. Mayers, a citizen of the United States, residing at Cleveland, in the county of Cuyahoga and State of Ohio, have invented a new, original, and ornamental Design for Woman's Shoe, of which the following is a specification, reference being had to the accompanying drawing, forming a part thereof.

Fig. 1 is a perspective view of a woman's shoe showing our new design;

Fig. 2 is a top plan view; and

Fig. 3 is a side elevational view thereof.

We claim:

The ornamental design for a woman's shoe, substantially as shown.
